UNITED STATES PATENT OFFICE.

JOHN E. MUHLEFELD, OF SCARSDALE, AND VIRGINIUS Z. CARACRISTI, OF BRONXVILLE, NEW YORK.

STEAM-BOILER STRUCTURE.

Original application filed April 17, 1920, Serial No. 374,721. Divided and this application filed August 14, 1922. Serial No. 581,645.

This invention relates to steam motive power and has for its primary object to provide an improved locomotive boiler structure of maximum steam generating capacity and constitutes a division of our prior application for patent filed April 17th, 1920, Serial No. 374,721.

More particularly, our invention comprehends the provision of a rigid and safe boiler structure consisting of a combination of water and fire tubes, a plurality of water circulating drums and a steam generating cylinder, through which the gases of combustion pass, with spaced water legs rigidly uniting the drums and the cylinder. By means of this improved boiler structure we aim to increase rigidity and thereby obviate vibration to a large extent and relieve the parts of undue strains and stresses which have a tendency to promote rupture and leakage.

It is also an object of our invention to provide means in the nature of a fuel economizer for utilizing the waste gases for the purpose of heating the boiler feed water. To this end we have provided a novel arrangement of dampers controlling the passage of the products of combustion through the smoke box of the locomotive whereby such products will be first directed into contact with the superheater units and then caused to impinge upon the walls of the feed water reservoir both when the locomotive is in operation and when it is not using steam.

Our invention also contemplates an improved exterior arrangement of the steam delivering pipe connection between the superheater and the boiler water leg constituting the steam collecting dome, together with a steam separator and a throttle valve interposed in said pipe connection.

In addition to the above three features, we also provide an auxiliary superheater arranged in the locomotive cab or other suitable location for the purpose of supplying either saturated or superheated steam for the operation of the reversing gear, air pump, grate mechanism, feed water pump, lubricator and other mechanical accessories with which the locomotive may be equipped and which are now operated by saturated steam.

With the above and other objects in view the invention consists in the improved construction, combination and relative arrangement of the several parts, as will hereinafter

be more fully described, illustrated in the accompanying drawings, and incorporated in the subjoined claims.

In the drawings, wherein we have illustrated one practical embodiment of our invention, and in which similar reference characters designate corresponding parts throughout the several views:

Figure 1 is a side elevation of a locomotive diagrammatically illustrating the salient features of our invention.

Figure 2 is a longitudinal section through the locomotive boiler, certain parts being broken away.

Figure 3 is a transverse section taken on the line 3—3 of Figure 1.

Figure 4 is a fragmentary section taken on the line 4—4 of Figure 3.

Figure 5 is a transverse section taken on the line 5—5 of Figure 1.

Figure 6 is a similar section taken on the line 6—6 of Figure 1.

Fig. 6^a is a similar sectional view taken in advance of the front water leg.

Figure 7 is a vertical sectional view through the smoke box of the locomotive, showing one of the feed water reservoirs arranged therein, and illustrating the arrangement of the draught dampers when the locomotive is in operation.

Figure 8 is a similar view showing the arrangement of the dampers when the locomotive is not in operation.

Figure 9 is a detail vertical section illustrating the connection between the dry pipe and the steam receiving header.

Referring in detail to the drawings, wherein we have illustrated a locomotive which may be either of the simple, compound, triplex or other type, the locomotive structure is mounted and supported in proper balance upon the main drive trucks 5 and the front and rear trucks 6 and 7 respectively. As is well known, in the customary locomotive construction the wheels of the latter trucks exert no positive tractive effort upon the rails as an aid in the propulsion of the locomotive, but constitute merely auxiliary guiding and supporting means. However that portion of the weight of the locomotive which devolves upon the wheels of the rear truck 7 results in a high adhesive pressure of these wheels upon the track rails. We have provided a supplementary drive means for the wheels of the rear truck 7 which is fully described and

claimed in a second prior application for patent filed June 24th, 1920, Serial No. 391,326, and accordingly, will not be herein further referred to in detail.

5 The locomotive boiler, as herein shown, includes a pair of laterally spaced upper drums 8 which extend substantially the entire length of the boiler structure, and a pair of laterally spaced relatively short lower drums 9. The latter drums extend rearwardly of the cylinder or shell 10. A water leg 11 is secured upon the upper portion of the cylinder 10, which is in communication with said water leg through the openings 12 in the cylinder wall. The forward ends of the drums 8 are supported in said water leg and communicate therewith through the openings 13, the water leg walls having steam-tight connection with the wall of the drum.

10 15 20 The intermediate water leg 14 connects the rear end of the cylinder 10 with the upper and lower pairs of drums 8 and 9, and these drums communicate with the water leg 14 through the openings 15 and 16 respectively.

25 The drums 8 and 9 are connected to each other at their rear ends by means of a third water leg 17, said drums communicating with the water leg through the openings 18 and 19, respectively.

30 35 The lower drums 9 extend through the fire box at either side of the grate 20, said fire box having refractory or other suitable side walls 21 covered by the insulating material or lagging 22.

40 Banks of vertically disposed water tubes 23 extend between and connect the upper and lower drums 8 and 9 at each side of the fire box to each other. These tube banks extend between the water leg 17 and the rear end of the cylinder 10.

45 A series of water circulating conduits 24 extend longitudinally through the fire box and are inclined rearwardly and downwardly from the front water leg 17 to the intermediate water leg 14. Between the rear ends of said conduits and the grate 20 a bridge wall 25 is built and a baffle wall 26 is arranged upon the upper sides of the conduits 24, and extends from the bridge wall 25 to a point adjacent the water leg 17. This baffle wall at its side edges is adjacent to the banks of tubes 23. It will thus be apparent from reference to Figure 4 of the drawings that the greater volume of the products of combustion gases can only escape from the combustion chamber in a lateral direction by passing between and in contact with the tubes 23. The flame and gases are in this manner drawn by induction through the tube banks, and then forwardly through the fire tubes 27 which extend longitudinally through the cylinder 10. These tubes at 60 65 their rear ends are fixed in the rear wall of

the water leg 14, and have their forward ends fixed in the front cylinder head 28.

An arch wall 29 spans the space between the drums 8 and immediately below this wall additional water tubes 30 are arranged and connect the water legs 14 and 17 to each other. Through the water leg 17 spaced flues 31 are disposed, and fixed at their ends to the header walls. Each of the tubes receives an auxiliary superheater unit 32, of a superheater located in the engineer's cab 33, which furnishes superheated steam for the operation of the air pump and other mechanical accessories of the locomotive.

70 75 80 85 The primary superheater indicated at 34 is arranged in advance of the cylinder 10 and the usual superheater units are provided and extend into the front ends of the fire tubes 27. The saturated steam header is connected by the steam delivery pipe 35 to the upper and central portion of the intermediate water leg 14, which serves in the capacity of a steam dome. Any approved means may be employed for establishing a steam-tight connection between the pipe 35 and the water leg. As seen in Figure 9 of the drawings, for this purpose we provide the wall of the water leg 14 with a flanged nipple 36, with which the flanged end of the pipe 35 is engaged. Collars 37 and 38 are respectively engaged on the pipe 35 and nipple 36, and are connected by the clamping screws 39. By this means the abutting flanges may be securely clamped in tight engagement with each other.

end with a smoke box 44, having the stack outlet 45. In the upper part of the smoke box and above the flues 27 a feed water tank or reservoir 46 is arranged. Preferably, 5 one of these reservoirs is located at each side of the stack 45. A vertical plate or diaphragm 47 separates the smoke box from a chamber 48 in which the primary superheater headers and units are located. A 10 main damper plate 49 is pivotally mounted at its lower end, as at 50, and is movable between the upper edge of the diaphragm 47 and a stop flange 51. At its lower end the diaphragm is provided with an opening 52 15 and a second pivotally mounted damper plate 53, controls the passage of the products of combustion through this opening. The damper plates 49 and 53 are connected to each other by a rod 54, whereby said 20 damper plates may be operated in unison. Each of the reservoirs 46 is preferably of cylindrical form, and is provided with a plurality of open ended tubes 46' extending longitudinally therethrough, and through 25 which the products of combustion may freely pass.

In Figure 7 of the drawings we have illustrated the arrangement of the damper plates when the locomotive is in operation. From reference to said figure it will be seen that the damper plate 49 is in contact at its upper end with the upper edge of the diaphragm 47, while the damper plate 53 is in an open position. Thus the induced 30 draught created by the steam nozzle draws the main products of combustion upwardly into contact with the superheater units, which extend into the forward ends of the tubes 27, and hence through the tubes 46' of 35 the feed water heater.

A horizontally disposed plate 70 surrounds the lower end of the stack 45 and between the steam nozzle 71, the plate 70 and the vertical diaphragm 47 a sheet of heavy 40 wire netting or perforated plate 72 is arranged, through which the products of combustion are drawn after passing through the tubes 46'. Thus any cinders will impinge against and be broken up by the netting or 45 by other equivalent means, be deposited in the smoke box, and not projected through the stack outlet.

When the locomotive is not being operated, or the steam used, the damper plates are disposed in the position shown in Figure 8, 50 wherein the upper end of the plate 49 is engaged with the stop flange 51, thereby stopping the flow of the gases through the superheater flues while the plate 53 is disposed 55 in its closed position over the opening 52. The gases through the lower boiler tubes now take the course indicated by the arrows, and are drawn upwardly in advance of the plate 49, hence through the tubes 46' and 60 around the reservoirs 46 and finally through

the foraminous wall 72 out through the stack 45. Thus in either arrangement of the damper plates it will be seen that the gases are caused to travel through the tubes 46' and to also contact with the body wall of 70 the feed water reservoir 46, thus highly heating the water therein before it passes to the reservoir outlet for delivery into the boiler. In this manner considerable economy in the 75 consumption of fuel may be realized, and heat, which has heretofore been wasted is conserved and advantageously employed, both when the locomotive is, and is not, using steam.

It will be understood, of course, that when 80 the damper plates are disposed, as seen in Figure 7, the products of combustion issuing from the lower fire tubes 27 will pass directly through the opening 52 and be exhausted through the stack 45.

From the above description it will be seen that we have devised a very novel locomotive boiler structure, the several units of which are so correlated and rigidly secured 85 to each other as to practically eliminate relative vibration. Thus torsional strains or 90 stresses tending to weaken or disrupt the joint connections between the parts of the water and steam circulating system will be obviated. The weight of the locomotive 95 structure is so distributed and balanced between the main drivers 5, the front supporting truck 6 and the rear supplementary drivers 7 that a considerable adhesive pressure is exerted by the latter upon the rails. In view of the fact that the boiler has a 100 very high steam generating capacity, the power necessary for the operation of the supplementary drive wheels will not lessen or detract from the power applied to the 105 main drive wheels 5.

It is to be understood that while we have herein shown and described one practical and satisfactory embodiment of the several 110 combination features of our improved locomotive, these features may nevertheless be exemplified in various other alternative structures, and we accordingly reserve the privilege of adopting all such legitimate 115 changes as may be fairly embodied within the spirit and scope of the invention as claimed.

While this particular description relates to a boiler adapted for a locomotive, such 120 boiler may also be used for other stationary or mobile purposes, as for example, for steamship or road or farm tractors.

We claim:

1. In a steam locomotive, a fire box and a 125 fire tube boiler extending forwardly therefrom, upper and lower drums arranged in pairs at opposite sides of the fire box, said lower drums terminating at the rear end of the boiler and the upper drums extending forwardly over the boiler, a front water leg 130

- connecting the forward ends of the upper drums with the boiler and affording communication therebetween, a rear water leg connecting the rear ends of the upper and lower drums with each other, and an intermediate water leg rigidly connecting the upper drums with the rear end of the boiler and with the forward ends of the lower drums. 50
10. 2. In a steam locomotive, a fire box and a fire tube boiler extending forwardly therefrom, upper and lower drums arranged in pairs at opposite sides of the fire box, said lower drums terminating at the rear end of the boiler and the upper drums extending forwardly over the boiler, a front water leg connecting the forward ends of the upper drums with the boiler and affording communication therebetween, a rear water leg connecting the rear ends of the upper and lower drums with each other, an intermediate water leg rigidly connecting the upper drums with the rear end of the boiler and with the forward ends of the lower drums, and a dry pipe connected to the intermediate water leg at its upper end and extending forwardly therefrom between the upper drums exteriorly of the boiler. 60
15. 3. In a steam locomotive, a fire box and a fire tube boiler extending forwardly therefrom, upper and lower drums arranged in pairs at opposite sides of the fire box, said lower drums terminating at the rear end of the boiler and the upper drums extending forwardly over the boiler, a front water leg connecting the forward ends of the upper drums with the boiler and affording communication therebetween; a rear water leg connecting the rear ends of the upper and lower drums with each other, an intermediate water leg rigidly connecting the upper drums with the rear end of the boiler and with the forward ends of the lower drums, and additional water and steam circulating connections between the boiler and the upper drums between the intermediate and front water legs. 70
20. 4. In a steam locomotive, a fire box and a fire tube boiler extending forwardly therefrom, upper and lower drums arranged in pairs at opposite sides of the fire box, said lower drums terminating at the rear end of the boiler and the upper drums extending forwardly over the boiler, a front water leg connecting the forward ends of the upper drums with the boiler and affording communication therebetween, a rear water leg connecting the rear ends of the upper and lower drums with each other, an intermediate water leg rigidly connecting the upper drums with the rear end of the boiler and with the forward ends of the lower drums, and a dry pipe connected to the intermediate water leg at its upper end and extending forwardly therefrom between the upper drums exteriorly of the boiler. 80
25. 5. In a combination water and fire tube boiler, spaced rear and intermediate water legs, a main boiler cylinder extending forwardly from the intermediate water leg and having fire tubes extending through said water leg, a front water leg extending above the boiler cylinder and communicating therewith, an upper pair of steam and water circulating drums mounted in said front, intermediate and rear water legs extending forwardly over the boiler cylinder and communicating with the respective water legs, pipe connections between each of said drums to the boiler cylinder disposed between the front and intermediate water legs, a pair of relatively short lower steam and water circulating drums mounted in the rear and intermediate water legs and communicating therewith, and a vertical bank of water tubes connecting each of said lower drums with the corresponding upper drum rearwardly of the boiler cylinder. 90
30. In testimony that we claim the foregoing as our invention, we have signed our names hereunder.
- JOHN E. MUHLFELD.
